(57) **CLAIM**

The ornamental design for a fitness chair, as shown and described.

DESCRIPTION

FIG. 1 is a front, left and top perspective view of a fitness chair showing our new design;

FIG. 2 is a front, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view showing the fitness chair in an alternate configuration; and,

FIG. 10 is another perspective view showing the fitness chair in the alternate configuration.

The broken lines in the figures illustrate portions of the fitness chair that form no part of the claimed design, and the dot-long dash-dot broken lines in the center of the fitness chair form no part of the claimed design.

1 Claim, 10 Drawing Sheets
